CEMENTING MACHINE FOR FLEXIBLE MATERIAL HAVING A WORKTABLE AND EXTENDED GUIDE ROLLS

Walter P. Osgood, Malden, Mass., assignor to Boston Machine Works Company, Lynn, Mass., a corporation of Massachusetts

Application April 17, 1951, Serial No. 221,454

2 Claims. (Cl. 118—250)

1

This invention relates to improvements in cementing machines such as that described and illustrated in my application, Serial No. 155,543, filed April 12, 1950. The machine described in said application is designed to guide pieces of flexible material such as cloth or soft leather, which may be of irregular shapes, from a stationary work table to a rotating horizontal coating roll which dips into a pool of suitable liquid adhesive. The coated work pieces are effectively stripped from the roll by suitable means.

There are occasions when it is desirable to coat a portion only of the work piece. For example, it may be desirable in cementing a lining to a vamp piece for a shoe upper to coat only a portion of the vamp piece leaving the toe portion uncoated so that after the lining piece is stuck to the vamp piece, a toe stiffener can thereafter be inserted between the uncoated portions.

According to the present invention, the feed rolls by which the work pieces are conducted into proper contact with the coating roll are extended out beyond an end of the coating roll to accommodate the portion of the work piece which is not to be coated.

Another feature of the present invention is the provision of improved adjusting means for a blade or doctor which is mounted with its edge close to the ascending side of the coating roll so as to regulate the thickness of the film of liquid carried up from the pool on the surface of the roll to be applied to the work pieces which are brought into contact therewith.

For a more complete understanding of the invention, reference may be had to the following description thereof and to the drawing of which—

Figure 1 is a rear elevational view of a portion of a cementing machine embodying the invention;

Figure 2 is a plan view of the same;

Figure 3 is a fragmentary sectional view of the same; and

Figure 4 is a fragmentary sectional plan view of a portion of the doctor blade and its adjusting means taken along the line 4—4 of Figure 3.

The cementing machine, portions of which are illustrated on the drawing, includes an open trough or reservoir 10 in which is mounted a horizontal coating roll 12. The roll is supported at one end by a fixed center element 14, the other end being supported by a shaft 15 by which the roll may be rotated at constant speed so as to pick up a film of liquid cement from a pool 16 of such cement in the trough 10. A pair of feed rolls 20 and 22 are supported by a suitable frame

10 24 above the coating roll 12 as indicated in Figure 3 and cooperate with the coating roll 12 to feed the work pieces through the machine. Adjacent to the front feed roll 20 is a horizontal work table 26 on which may be supported a work piece 28 which is to be put through the machine so as to have a coat of liquid cement applied to a face thereof. The machine illustrated is particularly adapted to coat pieces of flexible material such as soft thin leather, cloth or the like which may have been cut into irregular shapes, as, for example, pieces of leather which are to be assembled to form a shoe upper. The feed rolls 20 and 22 are preferably driven in the directions indicated by the arrows in Figure 3 so that a work piece will be fed and guided over the roll 20 and under the roll 22, these rolls being near enough to each other and to the coating roll 12 for frictional feeding engagement with the work piece. The work piece is stripped from the coating roll 12 by suitable stripping fingers 30 mounted against the rear side of this roll.

According to the present invention, provision is made for conveniently handling work pieces, a portion only of a face of which is to be coated, the remainder of the face being left uncoated. For example, a work piece 28 which is illustrated in Figure 2 may be shaped to form the vamp portion of a shoe upper. When coating the under face of this work piece, it may be desirable to apply coating to parts of the wing portions, leaving the rest of the piece uncoated. Thus, as far as the areas to be coated are concerned, there is a discontinuity in the engagement of the work piece with the coating roll. According to the present invention, this discontinuity does not result in an interruption in the feeding of the work piece through the machine as the feeding is continued by the engagement of the toe portion of the work piece with extended portions of the feed rolls 20 and 22. To guide the work pieces to the feed rolls, I provide a table 26 the width of which is about the same as the length of the coating roll. The feed rolls 20 and 22 are extended beyond the end of the coating roll 12, as indicated in Figure 1, so as to accommodate the portion of the work piece which is not to receive a film of cement and which therefore extends beyond the outer side edge of the table 26. This outer side edge of the table is preferably substantially aligned with the outer end of the coating roll 12 and thus serves as a convenient guide or indicator of the boundary between the part of the work piece which is to be coated and the part which is not.

The portions of the rolls 20 and 22 which are intersected by the planes of the ends of the coating roll 12, are circumferentially grooved as at 32 so that cement film from the pool 16 which is bulged slightly at the end edges of the coating roll 12 by surface tension will not come in contact with the feed rolls 20 and 22.

In order to control the thickness of the layer of cement carried up from the pool 16 by the surface of the coating roll 12, a doctor blade 40 10 is mounted on the front side of the trough 10 so that its edge 42 is parallel and adjacent to the surface of the coating roll 12. The doctor blade 40 is secured to a lip or flange 44 of the trough by suitable bolts 46 which are threaded through the blade and are received in notches 48 in the lip 44, wing nuts 50 being clamped to the bolts by locking nuts to convert the bolts to wing bolts. Each blade 40 is provided with two lugs 52 on its under face, one such lug being indicated in Figures 3 and 4. Through each lug is screw threaded a machine screw 54 having a lock nut 56 thereon, these screws being offset from the plane of the blade to abut the lip 44 of the trough 10. An initial adjustment of the blade 40 is made by pushing the blade manually toward the roll 12 and adjusting the screws 54 in such a manner that the edge 42 of the blade has a minimum clearance from the surface of the roll 12. The nuts 56 are then set up tightly to lock the screws 54 in such adjusted position. The blade cannot thereafter be pushed into contact with the surface of the roll 12 since the screws 54 act as permanent stops to prevent such contact. If more clearance than the minimum is desired, this may be obtained by means of a second pair of adjusting screws 60 which are threaded through the lugs 52, thus being offset from the plane of the blade so as to engage the edge of the lip 44. Each adjusting screw 60 may be provided with a knurled head 62 to facilitate manual operation thereof. A compression spring 64 is preferably mounted between the head 62 and the lug 52 so as to insure a frictional engagement between the screw 60 and the threaded hole through the lug 52 so that incidental rotation of the screw 60 will be prevented. By turning the screw heads 62 in one direction, the blade 40 can be readily adjusted away from the roll 12 so as to increase

the clearance and thereby increase the thickness of the film of cement lifted from the pool by the coating roll. By turning the screws 60 in the other direction, the blade can then be pushed closer to the roll, but the limit stop screws 54 prevent actual contact of the blade with the roll.

I claim:

1. In a cementing machine which includes an open reservoir for liquid cement, a horizontal coating roll in said reservoir, and means for supporting and rotating said roll; two horizontal feed rolls above said coating roll and in operative position relative thereto, said feed rolls having substantially continuous extensions projecting a substantial distance beyond an end of said coating roll and independent of said coating roll to guide portions of work pieces which are not to be coated, means revolubly supporting said rolls, and a work table supported adjacent to said feed rolls.

2. In a cementing machine which includes an open reservoir for liquid cement, a horizontal coating roll in said reservoir, and means for supporting and rotating said roll; two feed rolls 25 spaced above and near said coating roll and having circumferential grooves therein opposite the ends of the coating roll, said feed rolls having substantially continuous extensions projecting a substantial distance beyond an end of said coating roll and independent of said coating roll to feed portions of work pieces which are not to be coated, means revolubly supporting said feed rolls, and a work table having a width substantially equal to the length of the coating roll and 30 means supporting said table with an edge adjacent to said feed rolls.

WALTER P. OSGOOD.
